UNITED STATES PATENT OFFICE.

DUNCAN A. McCONNELL, OF ARLINGTON, NEW JERSEY, ASSIGNOR TO LOVELL-McCONNELL MANUFACTURING COMPANY, OF NEWARK, NEW JERSEY, A CORPORATION OF DELAWARE.

DIAPHRAGM-HORN.

1,232,583.

Specification of Letters Patent. Patented July 10, 1917.

Application filed December 8, 1914. Serial No. 876,008.

To all whom it may concern:

Be it known that I, DUNCAN A. McCONNELL, a citizen of the United States, and resident of Arlington, in the county of Hudson and State of New Jersey, have invented certain new and useful Improvements in Diaphragm-Horns, of which the following is a specification.

This invention relates to certain improvements in that type of diaphragm horns in which the diaphragm is caused to vibrate by the engagement therewith of a suitable rotor driven at the desired high speed by multiplying gearing and a one-way clutch interposed between said rotor and a manually and intermittently operated driving member.

My invention relates to certain details of construction whereby I secure greater compactness and render the device more easily operated, more quickly assembled and more efficient in operation. The various important features will be particularly pointed out hereinafter in connection with a detailed description of a preferred embodiment of my invention which I have selected for illustration in the accompanying drawings, in which similar reference characters indicate corresponding parts in the several views.

Figure 1 is a side elevation of a device constructed in accordance with my invention, a portion of the casing and the diaphragm being shown in section;

Fig. 2 is a side elevation similar to Fig. 1 but showing the operating mechanism as viewed from the opposite side;

Fig. 3 is a top plan view of the operating mechanism, the casing, diaphragm, and rack bar being shown in section;

Fig. 4 is a section on the line 4-4 of Fig. 1 and

Fig. 5 is a side elevation showing a different form of rack bar stopping means.

In the specific form illustrated, there is employed an elastic diaphragm 10, preferably made of thin spring steel, clamped at its periphery between two casing members 11 and 12, suitable gaskets or washers 13 being employed on opposite sides of the diaphragm. The casing member 11 has its body portion spaced from the diaphragm and has a large central sound outlet bordered by an outwardly directed flange 14

serving to support the resonator 15. The rear casing member 12 is substantially in the form of a cup with a cylindrical peripheral wall 16 closed at one end by an end wall 17 and having an outwardly extending peripheral flange 18 at the open end, and serving as the diaphragm clamping portion. The two members 11 and 12 may be rigidly secured together in any suitable manner, as for instance, by screws 19 extending through the peripheral portion of the diaphragm and the washers. The details of construction so far described form no portion of the present invention and may be varied in any described manner.

A wear-piece in the form of a threaded stud 20 extends through the diaphragm at the center thereof and has the end projecting toward the rear casing member rounded and symmetrical with respect to its axis to constitute a universally presentable wear surface. The diaphragm at the center is preferably reinforced to better support the stud, said reinforcing being preferably in the form of a tubular rivet comprising a sleeve 21 having a base flange engaging with one surface of the diaphragm and a collar riveted down into firm engagement with the other. For holding the wear-piece in proper adjusted position, a suitable lock nut 22 may be employed. Within the rear casing I mount a rotor 23 having a series of peripheral projections, preferably in the form of spaced cams, for successive engagement with the wear-piece to force the diaphragm into vibration as said rotor is turned at high speed. I prefer a cam of the same size and shape as that shown in Hutchison Patent No. 1,169,721 issued January 25, 1916, the drawing of which is substantially a working drawing of the horn as actually built and put upon the market, but as pointed out hereinafter, variations are possible. The rotor is preferably mounted to turn about an axis disposed substantially horizontal and substantially parallel to the diaphragm.

The specific means for supporting the rotor and its driving mechanism preferably includes a bracket having a base portion 25 rigidly secured to one wall of the casing, for instance, the rear end wall 17, and projecting bearing portions 26. The rotor 23 is mounted upon a shaft 27 which latter also

carries a pinion 28, the rotor and pinion being rigidly connected with each other preferably by being made rigid with the shaft. The bracket also supports a shaft 29 carrying gear 30 and ratchet wheel 31 rigidly secured together by suitable means, as for instance, by the sleeve 31^a rotatably mounted upon the shaft 29 which in this case is a stud shaft screwed tightly into the bracket. This shaft also carries a gear 32 which is rotatable independently of said pinion 30 and ratchet wheel 31. The latter are preferably spaced apart, said gear 32 being loosely mounted on the sleeve which connects them. This gear wheel 32 meshes with the pinion 28. On the side face of the gear wheel 32 is a pawl 33 held in engagement with the teeth of the ratchet wheel by a spring 34 also carried on the side face of the gear wheel.

A third shaft 35 journaled intermediate of its ends, has on one end a gear wheel 36 meshing with the pinion 30, and on the other end a pinion 37 meshing with a vertically movable rack bar 38. This rack bar is slidably mounted within a suitable guide-way 39 formed integrally in the material of the bracket and closed in not only at the sides but also at the back so that the bar is held in proper mesh with the gear 37 without the necessity of separate guide way members. Moreover, it serves to retain and protect from oxidation sufficient oil or grease to thoroughly lubricate the bar and to shed water falling on the exposed parts of the bar in bad weather. The upper end of the rack bar projects through a guide 40 projecting above the upper side of the casing and terminates in a head or handle 41 normally spaced at some little distance above the casing. By forcing the rack bar downwardly, the gear 37 is caused to rotate and motion is transmitted from this gear to the rotor 23 through the shaft 35, gear 36, pinion 30, ratchet wheel 31, pawl 33, gear 32, pinion 28 and shaft 27. At the end of the stroke the rack bar may be returned to its initial position with a corresponding return movement of the gear 37, gear 36, pinion 30 and ratchet wheel 31. The latter may pass beneath the teeth of the pawl and there will be no return rotation of the rotor 23.

With the parts made in the proportions shown in the drawings and with normal conditions of operation, the successive downward strokes of the plunger will give distinct, separate, abruptly terminating signals, the speed of the cam running up each time high enough to cause the cam contacts to occur one for each natural swing of the diaphragm and falling back abruptly each time to zero. At the high speed referred to, there will be a momentary music-like tone, a pleasing effect and great carrying power.

Preferably the device is so constructed that the rack bar normally occupies a predetermined raised position to which it is automatically returned each time after it has been depressed or released. Various means may be employed for limiting the upward movement, such for instance as a stop on one of the gear members. As shown, the size of the gear 37 is such that it does not rotate through one complete revolution during the full downward movement of the rack bar, and in the periphery of the gear 37 is inserted a stop 42 in the form of a pin or set screw so positioned that it will come into engagement with one of the teeth of the rack bar when the latter is raised. As it prevents the tooth from entering between the corresponding teeth of the gear wheel, it limits the upward movement of the rack bar.

Instead of inserting the stop in the periphery of the gear 37 and permitting it to engage with the rack bar 38, I may use a stop 42^a as shown in Fig. 5. This stop is in the form of a screw threaded into an aperture in the side of the gear 37 and engaging with the end of a screw 42^b threaded into the bracket. By forming the stop as shown in Fig. 5, a somewhat larger contact surface is secured and thus wear or distortion, due to repeated contacts, is materially reduced.

For giving the rack bar its upward movement, I preferably provide a coil spring 43 which may be guided on a pin 44 and may extend into a bore or passage running lengthwise of the rack bar. The spring and pin at their lower ends preferably engage with the lower side of the casing and the spring at its upper end engages with the rack bar at the inner end of the passage so as to normally tend to raise the rack bar to its upper limiting position. Thus, no separate part is needed to hold the spring and pin, and the removal of the bracket from the casing permits the removal of the pin and spring. As previously stated, during the upward movement, the shaft, its gears 36 and 37, the pinion 30 and ratchet wheel 31 are rotated in the reverse direction from that in which they are rotated during downward movement, but the rotor 23, pinion 28 and gear 32 may rotate in one direction and may either continue rotating or may remain stationary during the upward movement of the rack bar, dependent upon the speed at which the rack bar is depressed, the size and momentum of the rotor and the resistance due both to the engagement of the rotor with the wear-piece and the accuracy and delicacy of the gears, bearings, etc.

To facilitate lubricating the device, I preferably provide a small oil chip 46 supported preferably by oil conveying tubes 130

leading to the bearings. As shown, the cup is supported by two tubes 47 and 48 leading to the bearings of the shafts 27 and 35, while a third tube 49 leads from the oil cup to a point directly above the ratchet wheel 31. For delivering oil to the oil cup, the top of the casing may be provided with a suitable plug 50 having an ordinary type of spring pressed closure such as is commonly employed to prevent the admission of dust and dirt to oil openings. By means of this construction, all of the bearings may be lubricated by admitting oil through a single opening, and the oil reservoir is supported solely by the conveyors of oil from said reservoir.

Having thus described my invention, what I claim as new and desire to secure by Letters Patent is:

1. An alarm or signaling device including a diaphragm, a casing secured to the periphery of the latter, a bracket within said casing and secured to one wall thereof, a rack bar projecting through the wall of said casing and slidably guided by said bracket, a series of three shafts supported by said bracket and all disposed parallel to said diaphragm, a pair of rigidly connected gears on one of said shafts and having one of said gears engaging with said rack bar, a pinion and a ratchet wheel rigidly connected together and mounted upon the second of said shafts and having said pinion engaging with the other gear on said first mentioned shaft, a gear loosely mounted on said second mentioned shaft and carrying a spring pressed pawl engaging with said ratchet wheel and a rigidly connected pinion and diaphragm vibrator carried by the third shaft and having said pinion in engagement with said loosely mounted gear wheel.

2. A horn or signaling device including a diaphragm, a casing secured to the peripheral portion thereof, a rotor within said casing for vibrating said diaphragm, an operating member extending to the exterior of said casing, power transmitting mechanism within said casing, between said member and said rotor, an oil cup within said casing but unattached thereto, a closure on said casing, and permitting admission of oil to said cup, and tubes for supporting said oil cup and at the same time serving to deliver oil to the bearings of said power transmitting mechanism.

3. A horn or signaling device, including a diaphragm, a casing for supporting the latter, a rotor within said casing, an endwise movable rack bar projecting through said casing into the interior thereof, a gear en-

gaging with said rack bar, a stop carried thereby and disposed between two adjacent teeth thereof for engaging with said rack bar to prevent further relative movement in the same direction, a spring tending to move said rack bar in said last mentioned direction, and multiplying gearing between said rotor and said gear wheel.

4. A horn or signaling device including a diaphragm, a casing for supporting the latter, a bracket within said casing and having a passage-way therethrough, a gear wheel mounted on said bracket, a rack bar movable endwise through said passage and engaging with said gear wheel and with the side of said passage opposite to said gear wheel to prevent lateral movement of the rack bar away from the gear wheel, a rotor carried by said bracket, and means for transmitting motion from said gear wheel to said rotor.

5. An alarm or signaling device including a diaphragm, a casing secured to the periphery of the latter, a bracket within said casing and secured to one wall thereof, a pair of shafts supported by said bracket substantially parallel to said diaphragm, a diaphragm vibrating rotor on one of said shafts at one side of said bracket, a pinion on the other of said shafts at the same side of the bracket, a rack bar slidably mounted in said bracket and meshing with said pinion, and multiplying gearing and ratchet and pawl connections at the opposite side of said bracket for transmitting one-way rotary motion to said rotor bearing shaft from said pinion bearing shaft.

6. An alarm or signaling device, including a diaphragm having a centrally disposed wear-piece, a cylindrical casing secured to the periphery of said diaphragm, a rack bar, a rack bar engaging pinion and a diaphragm vibrating toothed rotor within said casing for direct engagement with said wear piece, said bar, pinion and rotor being disposed in the central vertical longitudinal plane of said casing, a bracket within said casing for supporting said rack bar, pinion and rotor, and a train of multiplying gearing and ratchet and pawl connections at one side of said plane for transmitting one-way rotary motion to said rotor from said pinion.

Signed at Newark, in the county of Essex and State of New Jersey this first day of December A. D. 1914.
